UNITED STATES PATENT OFFICE.

EDWARD HENRY SCHAIT, OF UPPER MONTCLAIR, NEW JERSEY.

WRITING APPLIANCE.

Application filed November 26, 1921. Serial No. 517,976.

To all whom it may concern:

Be it known that I, EDWARD H. SCHAIT, a citizen of the United States, and resident of Upper Montclair, in the county of Essex and State of New Jersey, have invented a new and Improved Writing Appliance, of which the following is a full, clear, and exact description.

My invention relates to a writing appliance, and aims to provide a device of this character more particularly adapted for use by shorthand writers.

In connection with court reporting and similar work, it is a well appreciated fact that considerable difficulty has been experienced for the reason that words, and in many instances the entire sense of a paragraph is lost, when it becomes necessary for a stenographer to turn a page.

Thus with an ordinary notebook, when the stenographer reaches the bottom of the page, it is necessary to turn the same over. This takes but a second, but it is sufficient for the stenographer to fall behind the dictator, and in many instances a number of words are lost or the stenographer is forced to speed up to such an extent that the outlines are poorly made, and consequently illegible when transcribing.

With this in mind my present invention aims to provide a writing appliance which, as aforesaid, is primarily adapted for use in connection with court reporting, and similar work, and by means of which this difficulty will be overcome, in that in use, this appliance will present a fresh writing surface simultaneous with the movement of the operator's hand from the bottom of the sheet to the top thereof.

A further object of my invention is the construction of a device of the character stated by means of which the results aforespecified may be accomplished, and which will be capable of being manufactured at a nominal figure, the parts being of such a simple construction and arrangement as to virtually preclude of disarrangement or breakage.

Still other objects of this invention will become apparent in the annexed specification taken in connection with the drawings, which latter illustrate one practical embodiment thereof, and in which;

Figure 1 is a perspective view of my appliance.

Figure 2 is a plan view thereof.

Figure 3 is an end view of the same.

Figure 4 is a transverse sectional view taken along the line 4—4 and in the direction of the arrow indicated in Figure 5, and

Figure 5 is a sectional side view taken along the line 5—5 and in the direction of the arrows indicated in Figure 2.

Referring now more particularly to Figure 1 it will be seen that the device preferably includes a base portion 10 from which side walls 11 extend upwardly, these side walls supporting between their upper edges a platen 13 having offset portions at each side slightly raised above a writing surface 12 extending throughout the entire length of a platen 13. Said platen is connected to the side walls 11 adjacent one of its ends by hinged portions 14, and adjacent its opposite edge by a fastening portion 15, and has a pivotal movement longitudinally of said side walls.

Thus as has been indicated in Figure 4 in dotted lines, the platen 13 may be swung upwardly so that access may be had into the interior of the appliance for a purpose hereinafter specified. Now assuming that the interconnected plies of paper 16 are disposed within the interior aforementioned, as in Figure 5, it will be appreciated that the outermost portion 17 of said paper may be brought around the inner edge of the platen 13, to a position at which it lies upon the writing surface 12, between said offset portions, the outer end of said paper resting upon a roller 18 with which it is preferably forced, into intimate engagement by means of a spring pressed roller 19 bearing against its upper surface.

However, as has been shown in Figure 5, the outer end of the paper 17 preferably passes through a slot in the outer wall 20 of the appliance, and assuming that the roller 18 is revolved it will be appreciated that the paper will be fed from within the appliance over the platen 13, and thus through the slot in the outer wall 20. With a view of accomplishing this actuation of the roller 18, I preferably utilize an endless flexible member 21, which in the embodiment illustrated is in the nature of a chain passing around sprocket wheels 22 and 23, the latter being fixedly secured to the shaft of the roller 18. Also a series of actuating members 24 are associated with the flexible element 21, and thus it will be understood, assuming that the parts are in the position illustrated in Fig-

ures 2 and 5, and further assuming that the stenographer has reached a position in his notes adjacent the inner or lower edge of the appliance, or that his right hand is being cramped due to reaching a point adjacent the inner portion of the appliance, that he may simply engage one of the actuating members 24 with the left hand while writing and by pushing upwardly toward the outer 10 end of the device rotate the roller 18 through the medium of the chain 21 thereby feeding the paper through the slot in the outer wall 20.

Thus it will be understood that no time 15 will be lost in the turning of a leaf, in that it is necessary in any instance for a short-hand writer to move his hand outwardly, if for no other reason than for the purpose of avoiding cramping of his hand, and this 20 movement will as aforescribed, result in the presenting of a fresh sheet of paper, thus accomplishing both of these operations simultaneously, and reducing delay to a minimum.

25 Thus all of the objects set forth in the preamble of this specification have been accomplished, and it will further be understood that numerous modifications of structure might readily be resorted to without 30 in the least departing from the scope of my claims; which are;

1. A writing appliance including a platen presenting a supporting surface adapted to receive a strip of writing material, an endless element for moving said strip of material over said surface, and actuating means for said endless element connected thereto and operable only in one direction to move said strip from end to end over said surface.
2. A writing appliance including a platen providing a writing surface, and adapted to receive a strip of writing material, a roller arranged beyond said platen, a sprocket

wheel carried by said roller, a second sprocket wheel, a chain passing around both 45 of said sprocket wheels and extending parallel to a side edge of said platen, and actuating members carried by said chain.

3. A writing appliance including a base, side walls extending upwardly from said base, a platen hingedly carried between the upper edges of said side walls, a roller arranged adjacent the upper end of said platen, a spring pressed roller co-operating with the first named roller, a sprocket wheel 55 carried by said first named roller, a second sprocket wheel rotatably mounted in said side walls, a chain extending around both of said sprocket wheels and connecting the same together, and actuating members carried by said chain.

4. A writing appliance including a body portion, a platen carried thereby, means at one end of said platen for feeding writing material therefrom, an endless element supported by said body portion for operating said means, and actuating members secured to said endless element for operating the same.

5. A writing appliance including a body 70 portion, a platen carried thereby, means at one end of said platen for feeding writing material therefrom, an endless element extending longitudinally of said body portion for operating said means, and actuating 75 members secured to said endless element for operating the same.

6. A writing appliance including a platen presenting a supporting surface adapted to receive a strip of writing material, an endless 80 element for moving said strip over said surface, and actuating means for said endless element connected thereto and having a movement only in the direction of movement of said element.

EDWARD HENRY SCHAIT.
